(57) **CLAIM**

The ornamental design for a rear combination lamps for automobile body, as shown and described.

DESCRIPTION

FIG. 1 is a front view of rear combination lamps for automobile body showing the new design;

FIG. 2 is a left side view thereof;

FIG. 3 is a right side view thereof;

FIG. 4 is a top view thereof; and,

FIG. 5 is a perspective view thereof.

The transparent/translucent external covers (not shown) of the rear combination lamps for automobile body form no part of the claimed design. In addition, the broken line showing the automobile body is only for illustrative purposes and forms no part of the claimed design.
